ICE GRID FOR REFRIGERATORS

John Bobe Herlein, Morrison, Ill., assignor to
 Ice Cooling Appliance Corporation, Morrison,
 Ill., a corporation of Delaware

Application November 19, 1935, Serial No. 50,600

19 Claims. (Cl. 62—46)

This invention relates to household and commercial ice refrigerators, and the principal object of the invention is to provide a novel ice grid which will increase the efficiency of the ice for refrigeration purposes, the grid exposing only the bottom surface of the ice block to the circulating air within the refrigerator casing by a unique arrangement of parallel metal plates disposed edge wise to the ice block, which arrangement considerably increases the cold surface area along which the air passes, the air currents rising at the sides of the refrigerator casing and entering the grid from the end and passing along the grid plates to the center of the grid from whence the air currents drop into the food compartment, thereby causing the ice to melt substantially from the bottom side of the block only.

Another object of the invention is to provide a novel ice grid comprising a series of relatively long parallel metal grid plates disposed edge-wise to the block of ice, and extending from side to side of the ice compartment, with shorter metal grid plates interposed between the pairs of longer plates, together with an interlocking member disposed transversely of the grid plates and serving to render the grid rigid, to divert meltage, and to control air circulation.

A further object is to provide a grid having plates increasing in depth from side to center, and provided with recesses at their centers, the walls of which serve to divert the drip of ice meltage into a drip pan disposed below the grid; said recesses also serving to provide an unobstructed passage for air currents in passing downwardly through an axially disposed slot in the drip pan into the food compartment.

I will explain the invention with reference to the accompanying drawings which illustrate one practical embodiment thereof to enable others familiar with the art to adopt and use the same; and will summarize in the claims the novel features of construction, and novel combinations of parts, for which protection is desired.

In said drawings:

Fig. 1 is a vertical section through a refrigerator cabinet of the "one door" type, provided with my novel ice grid, the section being taken upon the line 1—1, Fig. 2.

Fig. 2 is a horizontal section through the refrigerator cabinet showing the arrangement of the ice grid, the section being taken on the line 2—2, Fig. 1.

Fig. 3 is a vertical section through the refrigerator cabinet and grid taken on line 3—3, Fig. 1. In the drawings my novel ice grid is illustrated

in connection with a refrigerator casing of the "one door" type having side walls A, top B, bottom C and a back D, and having a single door E at the front which when opened gives access to the ice compartment above the grid, and likewise access to the food compartment disposed below the grid. However my grid may be used in connection with other types of ice refrigerators having two or more doors, also with refrigerators having certain doors installed for icing purposes only.

The ice compartment, in the upper portion of the casing, is shown as provided at the sides A—A and back D with a rustless lining 7, the lower ends of which at the sides A—A of the cabinet are deflected inwardly as at 7a to form a support or bracket for the ice grid, hereinafter described. While the bracket portions 7a are shown integral with the lining 7 the same may if desired be formed separately therefrom and secured to the walls A—A in any desired manner. The lower ends of the bracket portions 7a are flanged inwardly as at 7b towards the center of the casing and then bent reversely as at 7c to clamp therebetween the inner ends of plates 7d extending from the side walls A—A of the casing, the plates 7d not only serving to stiffen the shelf supporting flanges 7b of the bracket portions 7a and to maintain same properly spaced from the side walls of the casing, but also serving to deflect the upwardly rising warmer air currents at the sides A—A of the casing below the grid inwardly towards and along the grid plates, as shown by the arrows in Fig. 1.

The ice grid comprises a series of parallel relatively long plates 4 with shorter plates 3 interposed between the plates 4 as shown in Fig. 2, the plates 3 and 4 being disposed edgewise to the bottom of a block of ice, and rigidly connected together by means of the interlocking bar 1, tie plates 5, and deflector plate 2 as hereinafter described. The ends of the longer plates 4 are notched to provide shoulders 4a adapted to rest upon the flanges 7b of the bracket portions 7a. In order to connect the plates 4 together, tie plates 5 extend over the tops of the plates 4 at their ends, the tie plates being flanged downwardly over the ends and under the bottoms of the shoulders 4a and secured thereto by welding or the like.

The upper edge of each longer plate 4 is horizontal, while the lower edge of each plate 4 slopes downwardly from each end towards the center, the plates thus increasing in depth from the ends towards the center. At the center of the lower

50

55

edge of each plate 4 is a relatively large triangular recess 4b for the purpose of permitting condensation on the plate 4 to be carried to either side of the recess and fall upon a drip pan 6 below the grid, hereinafter described.

The shorter grid plates 3, as shown in Figs. 1 and 2, are only about half the length of the plates 4 and have their ends 3a (Fig. 1) cut on a bevel sloping upwardly towards the center of the casing. The plates 3 otherwise have the same shape and configuration as the corresponding portions of the plates 4, and are likewise provided with relatively large triangular recesses in their lower edges corresponding in size and shape with the recesses 4b in the longer grid plates 4.

Extending across the tops of the assembled plates 3 and 4 at the center of the grid and disposed at right angles to the plates is an interlocking bar 1 serving three purposes; first, to permit the block of ice to initially slide over the ice grid in placing the block in the ice compartment; second, to resist any tendency of the ice block to shift laterally within the ice compartment in event the grid is not level; and third, to tend to split the ice block into two parts which will separate and slide laterally away from the deflector plate 2 hereinafter described. The interlocking bar 1 may be secured to the plates 3 and 4 in any desired manner preferably by notching the lower edge of the same to receive the upper edges of the plates 3 and 4 which may then be welded thereto. Obviously the upper edges of the plates 3 and 4 could be notched instead of bar 1, if desired.

35 The deflector plate 2 extends transversely of the grid and serves three purposes; first, to divert the meltage water to either side of the flue opening 6d; second, to serve as the upper part of the air flue; and third, to support and locate the shorter plates 3 of the grid; and as the deflector plate is secured to all of the plates 3 and 4 a very substantial construction is provided. The deflector plate 2 is slightly angular in cross-section (Fig. 1) with the apex of the angle disposed in a vertical plane passing through the center of each of the plates 3 and 4, and the side edges of the deflector 2 terminate at points substantially above the widest portions of the recesses 4b in the lower edges of the plates 3 and 4. Preferably the deflector plate 2 passes through correspondingly shaped openings or slots in the assembled plates 3 and 4 and is secured thereto by welding; and if desired the deflector 2 may be secured by welding to the interlocking bar 1.

55 At the rear end of the grid is a plate 4x (Fig. 3), the lower end of which is flanged downwardly and rearwardly as at 4y and extends under the lower edge of the lining 7 on the back wall D of the casing; while at the front end of the grid is a plate 4w having its lower end flanged downwardly and forwardly as at 4z to extend up to a portion of the center rail which is disposed across the front of the refrigerator casing.

65 The center rail preferably comprises a plate 9 extending across the entire front of the refrigerator casing between the side walls A—A at the height of the ice grid, the plate having its upper edge flanged obliquely downwardly as at 9a towards the ice grid to assist in maintaining the block of ice centered on the grid. The lower end of the plate 9 is flanged inwardly as at 9b. Below the lower edge of the flanged portion 9a is a plate 9c which forms a continuation of the flange 9a and slopes downwardly and rearwardly, and has its lower edge flanged downwardly as

5 at 9d to overlie the flanged portion 4z of the front plate 4w of the grid, as illustrated in Fig. 3. Below the lower end of and spaced from the plate 9d is a plate 9e extending downwardly to meet and stiffen the flange 9b which forms a shelf for supporting the front end of the drip pan 6 as shown in Fig. 3.

10 Drip pan 6 is preferably of the insulated type and consists of upper and lower flanged sheet metal members 6a, 6b with a layer of insulation 6c therebetween, the upper pan 6a serving as the lower half of the air flue and also as the drip pan. The lower pan 6b merely serves to protect the insulation 6c and to present a clean metal surface at the top of the food compartment. The drip pan 6 is spaced away from the side walls A—A of the refrigerator casing and is provided with a slot 6d at its center which slot extends the full length of the grid; and has a flange 6e around its edges retaining the meltage 15 water. To assist the flow of air along the plates 3 and 4 and also to assist in carrying off drainage water the sections of the drip pan at opposite sides of slot 6d slope downwardly towards the center of the casing. The front end of the drip 20 pan 6 is supported upon the flange 9b of the center rail 9, while the rear end is supported by angle clips secured to the rear wall D of the refrigerator casing, the drip pan 6 sloping generally 25 downwardly toward the rear of the casing (as shown in Fig. 3) so that the meltage water will flow into the drain tube 8.

30 The air circulation is illustrated by the arrows in Fig. 1, the warmer air passing upwardly along the side walls A—A of the food compartment, and inwardly towards the center of the casing in the air flue formed between the bottom of the block of ice and the drip pan 6, the air then passing along the grid plates 3 and 4, the major parts of the surfaces of which plates are exposed to the warm air. The chilled air is then passed downwardly through the slot 6d in the drip pan and is thus returned to the food compartment at its center.

35 The recesses 4b in plates 3 and 4 at their centers permit any condensation collecting on said plates to be carried to either side of the recesses and to fall upon the drip pan 6.

40 The brackets 7a, which may be integral with or separate from the refrigerator lining 7, extend along each side wall A from the front to the rear and serve to support the ice grid. These brackets 45 7a slope downwardly and inwardly so as to confine the block of ice to the space directly over the grid inasmuch as the ice chamber itself is somewhat larger than the blocks of ice. Obviously these inclined surfaces will tend to force the ice block directly over the grid, as will also the downwardly and rearwardly plates 9a, 9c of the center rail 9 which form continuations of the 50 bracket portions 7a.

55 The ice grid is illustrated herein in connection with a so-called "one door" refrigerator, although it is obviously applicable for use in refrigerators of two or more doors, and also to refrigerators 55 having certain doors installed for icing purposes only.

60 I claim:

65 1. An ice grid for refrigerators comprising a plurality of parallel vertically disposed grid 70 plates adapted to be disposed edgewise to a block of ice supported thereon; intermediate grid plates of shorter length substantially conforming in size and shape with the corresponding portions of the first mentioned plates; and a horizontally dis- 75

posed plate on the transverse axis of the grid connected with all the grid plates intermediate their upper and lower edges, and extending at right angles thereto.

5. 2. In a grid as set forth in claim 1, said grid plates increasing in depth from their ends towards their centers and having recesses in their lower edges below and of substantially the same width as the horizontal plate.

10. 3. In combination with a grid as set forth in claim 1, a bar disposed axially of the grid and extending above the upper edges of the grid plates, said bar being connected with the plates and arranged to be disposed edgewise to the block 15 of ice.

15. 4. An ice grid for refrigerators comprising a plurality of parallel vertically disposed grid plates arranged to be disposed edgewise to a block of ice supported thereon; said plates increasing in depth from their ends towards their centers and having in their central lower edge portions V-shaped recesses defining spaced depending drainage points; and means for connecting the plates together.

20. 5. An ice grid for refrigerators comprising a plurality of parallel vertically disposed grid plates adapted to be disposed edgewise to a block of ice supported thereon; intermediate grid plates of shorter length substantially conforming in size and shape with the corresponding portions 25 of the first mentioned plates; said grid plates increasing in depth from their ends towards their centers; and means for connecting the plates together.

25. 6. A refrigerator, comprising a casing having an ice compartment and a food compartment; an ice supporting grid between the compartments including a series of vertical substantially parallel grid plates disposed for edge-wise engagement with ice at the bottom of the ice compartment and extending from side to side thereof; means for supporting the grid plates; means for directing upwardly rising air currents at the sides of the food compartment inwardly along the grid plates below the ice block towards the transverse axis of the grid; a drip pan below the grid arranged to form with the bottom of the ice block an air flue and having a slot underlying the central part of the grid for the passage therethrough of cold air into the food compartment; and means for diverting the drippings of ice meltage above the slot into the drip pan.

30. 7. In a refrigerator as set forth in claim 6, each 35 of the grid plates increasing in depth from end to center, and having a recess at the center of its lower edge spanning the slot for diverting the drippings of ice meltage into the drip pan.

35. 8. In a refrigerator as set forth in claim 6, said 40 grid supporting means having portions adapted to center a block of ice upon the grid.

40. 9. In a refrigerator as set forth in claim 6, means on the grid for supporting a block of ice to initially slide thereover in filling the ice compartment.

45. 10. In a refrigerator as set forth in claim 6, a center rail extending from side to side of the casing across the front end thereof; said rail having a portion adapted to center a block of ice upon the grid.

50. 11. A refrigerator comprising a casing having an ice compartment and a food compartment; an ice supporting grid between the compartments including a series of parallel grid plates disposed 55 for edgewise engagement with ice at the bottom

of the ice compartment and extending from side to side thereof; intermediate grid plates of shorter length interposed between the first mentioned plates; means at the sides of the casing for supporting the first mentioned grid plates 5 and for directing the upwardly rising air currents at the sides of the food compartment inwardly along the grid plates below the ice block towards the axis of the grid; a drip pan below the grid arranged to form with the bottom of the ice block an air flue having an axially disposed slot for the passage therethrough of cold air into the food compartment; and a deflector plate of greater width than the slot connected with all the grid plates above the slot, and diverting the 10 drippings of ice meltage above the slot into the drip pan. 15

12. In a refrigerator as set forth in claim 11, each of the grid plates increasing in depth from end to center, and having a recess at the center of 20 its lower edge spanning the slot for diverting the drippings of ice meltage into the drip pan.

13. In a refrigerator as set forth in claim 11, said grid supporting means having inwardly and downwardly inclined portions adapted to confine 25 a block of ice to the space directly over the grid.

14. In a refrigerator as set forth in claim 11, means on the grid extending thereabove for permitting a block of ice to initially slide thereover in filling the ice compartment; said means tending to subsequently split the block above the slot.

15. In a refrigerator as set forth in claim 11, a center rail extending from side to side of the casing across the front end thereof, said rail having an inwardly and downwardly inclined portion 30 adapted to confine the block of ice to the space directly over the grid; and said rail supporting the front end of the drip pan.

16. A refrigerator comprising a casing having an ice compartment and a food compartment; an 40 ice grid between the compartment including a series of parallel grid plates disposed edgewise to the bottom of the ice compartment and extending from side to side thereof; intermediate grid plates of shorter length interposed between and conforming in shape with the corresponding portions of the first mentioned plates; means at the sides of the casing for supporting the first mentioned grid plates and for directing the upwardly rising air currents at the sides of the food compartment inwardly along the grid plates below the top edges of the grid plates towards the axis of the grid, said supporting means having inwardly and downwardly inclined portions adapted to confine a block of ice to the space directly 50 over the grid; a drip pan below the grid arranged to form with the bottom of the ice block an air flue having an axially disposed slot for the passage therethrough of cold air into the food compartment; and a deflector plate of greater width 55 than the slot connected with all the grid plates above the slot, and diverting the drippings of ice meltage above the slot into the drip pan.

17. In a refrigerator as set forth in claim 16, each of the grid plates increasing in depth from 60 end to center, and having a recess at the center of its lower edge spanning the slot for diverting the drippings of ice meltage into the drip pan, said recesses providing unobstructed passage for air circulation through the slot.

18. An ice grid for refrigerators comprising a plurality of parallel vertically disposed grid plates arranged to be disposed edgewise to a block of ice supported thereon; and a horizontally disposed angular plate connected with the grid 70 75

plates and passing therethrough above their lower edges at right angles to the plates, said grid plates increasing in depth from their ends toward their centers defining downwardly converging lower edge portions on each grid plate and having recesses in their lower edges at their central portions.

19. In combination with a grid as set forth in

claim 18, a bar disposed transversely of the grid at right angles to the plates thereof and extending above the upper edges of the grid plates, said bar being connected with the plates and disposed edgewise to a block of ice.

5
